SYNCHRONOUS CLOCK SYSTEM

James W. Bryce, Bloomfield, N. J., assignor to
 International Business Machines Corporation,
 New York, N. Y., a corporation of New York

Application April 11, 1934, Serial No. 720,015

7 Claims. (Cl. 58—24)

This invention relates to a synchronized clock system and more particularly relates to the provision of an improved method for synchronizing secondary impulse clocks which are controlled by a so-called master clock.

The present invention is directed to actuation and synchronization of the secondary clocks under the control of a master clock by the agency of electrical energy and has for its object the utilization of impulses by an improved secondary clock mechanism for synchronizing the secondary clocks, which impulses are initiated and controlled by the master clock during successive periods of time.

Various other objects and advantages of my invention will be obvious from the following particular description of one form of mechanism embodying the invention or from an inspection of the accompanying drawings, and the invention also constitutes certain new and novel features of the construction and combination of parts hereinafter set forth and claimed.

In the drawings:

Fig. 1 is a wiring diagram by which secondary clocks may be actuated and regulated in the practice of the present invention.

Fig. 2 shows the position of the secondary clock mechanism just before release of the stop pawl.

Fig. 3 shows the position of the secondary clock mechanism when stop pawl is released.

Fig. 4 shows the position of the secondary clock mechanism during resetting of released stop pawl.

Master clock.—The master clock in its general details may be of any desired form. For example it may be that shown in my prior Patent No. 1,390,018. Referring to Fig. 1, the master clock includes the usual train adapted to drive the minute arbor 16 which makes one revolution per hour. The usual escapement mechanism 11 is provided. Fixed to the minute arbor is a cam 12 with two drop-off shoulders causing contacts 14 to be closed during the intervals between the successive releases of the two levers carrying said contacts.

Preferably, the arrangement of parts is such that the contacts 14 are normally open and are closed for two short intervals during a regular period of about one hour duration. It will be obvious, however, that by a proper rearrangement of the associated parts of the system these cam contacts could operate in a reverse manner being normally closed and opened during the short intervals in the hourly periods.

Also fixed to the minute arbor 10 is a cam 15 which is adapted to control the opening and clos-

ing of contacts 16. In the preferred embodiment, contacts 16 are arranged to close for a short period and then open prior to the sixtieth minute.

In addition, the master clock is provided with 5 the usual minute impulse contacts 17 which are controlled in the usual way from a minute cam 18 or otherwise as is the custom in clocks of this sort.

For accelerating the advance or forward movement of the secondaries quick acting contacts 19 are provided and preferably operated by attaching one of them to the escapement mechanism 11. These contacts will close at every movement of the escapement mechanism. 10

Secondary clock.—The secondary clock included in Fig. 1 is of conventional form and it includes a minute arbor shaft 20 which makes one revolution per hour. This shaft is preferably advanced by means of an impulse magnet 21 20 which acts through the usual ratchet wheel 22 to advance the minute arbor 20 step by step each time the magnet 21 receives an impulse from the master clock. Carried by the minute arbor 20 on each synchronizing clock is a cam disk 23 provided with a stud 24. Pivotal mounted at 25 is a locking pawl 26 supported by a suitable plate 27 (Fig. 2) in the secondary clock and adapted to cooperate with stud 24 when in the lower position as shown and held in this position by resilient 15 spring detent 28. Also pivotally mounted to plate 27 is lever 29, acted upon by springs 30 and 31 holding said lever in position, and loosely attached to arm 32 cooperating with cam disk 23 under influence of spring 33. Also loosely attached to lever 29 is link 34 connected to crank lever 35 pivotally mounted at 25 and engaging pin 36 secured to pawl 26. Adapted to engage pin 36 is another lever 37 rotatably mounted at 30 38 and loosely attached to arm 39 provided with 40 a protruding finger 40 adapted to cooperate with disk 23 by virtue of spring 41.

At the free end of arm 39 is an offset 42 adapted to be engaged by extension 43 of armature 44 when arm 39 is in the position shown in 45 Figs. 2 and 3. Armature 44 pivoted at 45 is provided with an extension arm 46 adapted to engage arm 32 when the described linkage is in a position as shown in Fig. 4 and to be described hereinafter. Assuming the linkage to be in position as indicated in Fig. 2, an impulse thru magnet 47 causes its armature 44 to be attracted and engage the offset 42 of arm 39 to force arm 39 downwardly as shown in Fig. 3. Downward movement of arm 39 causes lever 37 to urge pin 55

36 on pawl 26 upwardly to the position as indicated in Fig. 3 in which position the pawl 26 is retained by coacting spring detent 28 releasing the stud 24 on cam disk 23. After rotation of 5 the cam disk 23 in a clockwise direction for a short period another impulse thru magnet 47 causes its armature 44 to be attracted to engage the arm 32 displaced by the shoulder on cam disk 23. Arm 39 is not engaged by armature 44 10 when not located in the recess in cam disk 23 and arm 32 is not engaged by armature 44 unless displaced by the shoulder on the cam disk, the said recess and shoulder being so arranged on the cam disk that only one arm, either arm 39 or 15 arm 32 can be engaged by the attracted armature 44 at one time. Engagement of arm 32 by the said armature rocks the arm 32 and lever 29 to the right as shown in Fig. 4 to cause link 34 to urge crank lever 35 downwardly on pin 36 on 20 pawl 26 to restore pawl 26 to its former lower position and in the path of the stud 24 on the disk 23.

The disk is timed with reference to the minute hand of the secondary clock so that when the 25 minute hand indicates the 59th minute the stud on the disk will be close against the pawl 26. When the pawl is raised the stud will be freed as shown in Fig. 3.

Normal operation.—A full explanation of a 30 manner in which the method may be practiced will be described with reference to Fig. 1.

The first operation to be described will be the normal impulse operation for actuating the secondary clocks. For clarity, it will be assumed 35 that all of the secondary clocks are in a position immediately after the hour reading. Referring to the wiring diagram illustrated in Fig. 1 current is supplied from a battery indicated at 50 and the clocks are continuously actuated by minute 40 impulses through magnets 21 described above. It is understood that battery 50 is but a conventional designation for a source of electrical impulses and that other forms of impulses besides direct current impulses are within the scope of 45 this invention.

Current from battery 50 flows thru switch 51, line 52, contacts 17, magnet 53, line 54 to the common return ground. This current is intermittent due to the periodic closing of contacts 17 50 by cam 18 on the minute arbor of the master clock, and therefore contact 55 will be closed and opened at minute intervals. This will allow an intermittent current to flow from battery 50, line 56, line 57, contact 55, magnets 21 to common return ground, thus causing magnets 21 acting 55 through the ratchet 22 to advance the minute arbor 20 step by step as each minute impulse is received by magnet 21. All of the secondary clocks of the system will be actuated in this manner.

Synchronization.—Synchronization of the secondary clocks to the so-called master clock is maintained hourly by the master clock sending one impulse at some period during the hour and 60 at the same time an impulse energizing magnet 21 is delivered to the secondary system to energize magnets 47 to position locking pawl 26 into the path of stop 24 on cam disk 23 as described hereinbefore, and a second similar impulse later in the 65 same hour period for example the sixtieth minute impulse to energize the magnets 47 to raise the locking pawl 26 to free said stud 24. If any one of the clocks is fast, the minute arbor 20 of the secondary clock will be stopped by its pawl 26 70 until it has been retarded an amount sufficient 75

to bring it into synchronism with the master clock. The normal position of each pawl 26 as explained is in the path of its respective stud 24 on cam disk 23.

Should any of the clocks be slow they must be 5 stepped ahead at a rapid rate in order that they be on time on the hour. This is accomplished by causing rapid actuations of magnets 21 just before each hour reading of the hands of the master clock. Cam 15 closes contacts 16 preferably after the fifty-ninth minute and allows a branch current to flow from battery 50, switch 51, contacts 16, line 58, contacts 19, magnet 53, and line 54 to ground. Contacts 19 close in comparatively rapid succession, for example, once 15 every two seconds and causes the intermittent current set up to energize magnet 53 at the same rate. This results in closing contacts 55 at the same rate and current from battery 50 through lines 56 and 57 through contacts 55 is conducted 20 to magnets 21 thus producing rapid advance of any slowly timed secondary clocks.

In my preferred embodiment, this period of acceleration of the slow clocks occurs shortly after the fifty-ninth minute and lasts for about thirty 25 seconds, thus allowing for a positive correction of fifteen impulses each hour. This period may be lengthened if desired, but it must terminate prior to the closing of contacts 14, to cause the release 30 of stop 24, by cam 12 which is timed to close the contacts on the hour.

As stated before, the locking pawl 26 is raised when contacts 14 are closed and when magnet 47 is energized. Energization of magnet 47 occurs when contacts 55 are closed on the hour impulse. 35 Current then will flow from battery 50, line 56, line 57, contacts 55, line 59, contacts 14, line 60, magnet 61 to ground, energizing magnet 61 to close its contact 62, allowing current from battery 50 to flow thru line 56, contact 62 to magnet 40 47 to ground. Just prior to the hourly impulse the minute arbor of the synchronized clocks is in a position as shown in Fig. 2, the stud 24 is engaged by locking pawl 26, the extension 40 of arm 39 is cooperating with the recess in cam disk 23 45 and arm 32 is cleared of the shoulder on said disk. So that energization of magnet 47 at this period, namely, the hour impulse, attracts its armature 44 to engage and depress arm 39 to cause the locking pawl 26 to be raised and maintained in the raised position to free stud 24 as explained hereinbefore. Since contacts 14 and contact 62 are closed on the hour, locking pawls 26 will be removed from the paths of the studs 24 on disks 23 and all of the clocks will continue 55 their movement in synchronism.

At some period after the hour contacts 14 are adapted to be closed again by the second shoulder on cam 12, and at the same time the minute impulse contacts 17 are closed, for example, the 60 eighth minute, so that current again flows from battery 50 through lines 56 and 57, now closed contacts 55 due to energization of magnet 53 by the eighth minute impulse, line 59, contacts 14, line 60, magnet 61 to ground, energizing magnet 61 closing its contact 62. Current then flows from battery 50 thru line 56, contact 62, to magnet 47 and ground, energizing magnet 47. At the time the eighth minute impulse is transmitted the minute arbor of the secondary clocks is in a position 70 so that the shoulder on its attached cam disk 23 displaces the cooperating arm 32 to a position as shown in Fig. 4 so that the attracted armature 44 of the energized magnet 47 engages arm 32 to move it to the right as previously ex- 75

plained and in so doing causes the locking pawl 26 to be reset from its raised position as shown in Fig. 3 to its normal lower position as shown in Fig. 4 to be in the path of cam disk stud 24.

5 It will be apparent from the foregoing that the period of coincidence of all the clocks in the system described in this embodiment of my invention occurs after the fifty-ninth minute and may last until a few seconds before the sixtieth minute, allowing for an advance of slow secondary clocks of as much as fifteen minutes and a retardation of fast secondary clocks of a maximum amount of a little less than fifty two minutes. 10 It is manifestly obvious that the corrections may be relatively varied according to the timing of the various cams.

It will be understood that if in any case it is required to correct the time of the entire system, as for example, when the master clock is running fast or slow and this correction is to be within the range permitted by the synchronizing period it is only necessary to reset the hands of the master clock to the desired extent. The secondaries will then set themselves within the next hour. 15 If the amount is in excess of the synchronizing period for which the system is designed, for example, when a daylight saving correction is required, a manual control is brought into operation as shown in Fig. 1 which will now be described. Referring to the diagram a wire 65 is provided terminating in a switch point as shown. To retard the secondary clocks the switch 51 is displaced to the open or off position. This switch is maintained open for the desired retarding period. 20 If it is desired to advance the clock, the switch 51 is thrown to connect with the switch point or wire 65. The effect of connecting switch 51 with wire 65 is to cause the fast set-up contacts 19 to come into action and rapidly advance the various secondary clocks. The switch 51 will be held closed until the secondary clocks advance to the desired extent. For example to advance all of the clocks one hour with contacts 19 closing every two seconds it will take two minutes to 25 bring about the proper advance of the secondaries.

It will be understood that it is not essential to hold switch 51 closed for the exact period inasmuch as the synchronizing system will function 30 to bring the clocks in time with the master clock whether the said secondary clocks are fast or slow with respect to the master clock. It is only necessary that they be brought within the range of the synchronizing period.

55 The above is equally true with regard to retarding operations it being only necessary to open switch 51 for approximately the desired retarding period.

In Fig. 1, three secondary clocks are illustrated 60 showing their time relation to the master clock. The hands and cam disks 23 are shown as rotating in their normal direction.

As stated previously, at the hour all of the secondary clocks behind time will be urged ahead by the rapid series of accelerating impulses, but 65 since clock X is on time it will not be affected for locking pawl 26 is in the path of cam disk stud 24 and will hold the cam disk in position until the stud is freed. Clock Y is shown to be 15 minutes fast and its cam disk locked in position and held so until the hour, while clock Z which is indicated to be 15 minutes slow will continue to operate until it is picked up by the accelerating impulses occurring shortly after the fifty-ninth minute, 70

and moved ahead until the disk 23 is stopped by pawl 26. Following immediately after the cessation of the accelerating impulses, all the pawls 26 will be raised, and the secondary clocks will then continue to operate in synchronism with the master clock. 5

While there has been shown and described and pointed out the fundamental novel features of the invention as applied to a single modification, it will be understood that various omissions and 10 substitutions and changes in the form and details of the device illustrated and in its operation may be made by those skilled in the art without departing from the spirit of the invention. It is the intention therefore to be limited only as indicated by the scope of the following claims. 15

What is claimed is as follows:

1. A synchronized clock system including a master clock and a secondary clock, means in the master clock for sending normal driving impulses 20 periodically to the secondary clock, means in the secondary clock controlled by said impulses to advance it accordingly, a device controlled by the master clock for sending additional periodic impulses to the secondary clock, instrumentalities 25 for restraining advancement of the secondary clock when it reaches a certain chronological position, mechanism in the secondary clock positioned in accordance with the chronological position of the secondary clock, and means cooperat- 30 ing with said mechanism and controlled by the said additional impulses so that the receipt of one of such impulses renders the said restraining instrumentalities either to be subsequently effective to prevent further advancement of the secondary 35 clock or to release said restraining instrumentalities depending on the chronological position of the aforementioned mechanism.

2. A synchronized clock system including a master clock and one or more secondary clocks, 40 means in the master clock for sending periodic driving impulses to advance said secondary clocks, means controlled by the master clock for sending additional current impulses to the secondary clocks, blocking means movable into and 45 out of blocking position for restraining advancement of the secondary clock, means settable in accordance with the chronological position of the secondary clock for controlling said blocking means, and electromagnetic means controlled by 50 said additional impulses for moving said blocking means into or out of blocking position in accordance with the setting of said settable means.

3. A synchronized clock system including a master clock and one or more secondary clocks, 55 means in the master clock for sending periodic driving impulses to advance said secondary clocks, means controlled by the master clock for sending additional current impulses to the secondary clocks, blocking means movable into and 60 out of blocking position for restraining advancement of the secondary clock, a member movable with the chronological advancement of said secondary clock, a plurality of settable members co- 65 operating with said blocking means and said movable member and positioned in accordance with the chronological position of said movable member, and electromagnetic means common to said settable members for controlling the same to move the blocking means into or out of block- 70 ing position in accordance with the position of said settable members.

4. A synchronized clock system including a master clock and a secondary clock, means in the master clock for sending normal driving impulses 75

- periodically to the secondary clock, means in the secondary clock controlled by said impulses to advance it accordingly, means controlled by the master clock for sending additional periodic impulses to the secondary clock, means for restraining advancement of the secondary clock when it reaches a certain chronological position, settable means in the secondary clock positioned in accordance with the chronological position of the 5 secondary clock, means cooperating with said settable means during certain predetermined chronological positions of the secondary clock so that upon receipt of one of said additional impulses the settable means is controlled to render 10 said restraining means to be subsequently effective to prevent further advancement of the secondary clock beyond a certain chronological position, and said last-named means cooperating with said settable means during another predetermined 15 chronological position of the secondary clock so that upon receipt of a successive additional impulse the settable means is controlled to release the restraining means to permit advancement of said secondary clock.
- 20 5. A secondary clock including an electromagnet for advancing said clock, a blocking device for restraining advance of said secondary, a cam member driven by said electromagnet, a plurality of cam followers variably positioned at different 25 chronological positions of said cam member, connecting linkages cooperating with said cam followers and said blocking device, and electromagnetic means common to both cam followers for controlling one or the other to control the operation of said blocking device.
- 30 6. A synchronized clock system including a master clock and one or more secondary clocks, means in the master clock for periodically transmitting electric impulses for driving the second- 35 ary clocks, magnetically operated means in the secondary clocks for blocking advancement of said secondary clocks, said means being alternately movable into and out of blocking position on successive magnetic operations in accordance with the chronological position of said clock, and means in said master clock for transmitting periodic uni-directional current impulses to said magnetically operated means wherein successive uni-directional current impulses cause alternate 10 movement into and out of blocking position.
7. A synchronized clock system including a master clock and one or more secondary clocks, means in the master clock for sending normal driving impulses periodically to the secondary 15 clocks, means in the secondary clocks controlled by said impulses to advance the secondary clocks accordingly, means controlled by the master clock for sending additional uni-directional periodic impulses to the secondary clocks, an 20 electro-magnet in each secondary clock operable by said additional uni-directional impulses, means for restraining advancement of the secondary clocks when they reach a certain chronological position, means operable in a certain 25 chronological condition of the secondary clocks including means controlled by said electro-magnet upon operation by one of the said additional uni-directional impulses to render the said restraining means to be effective to subsequently 30 prevent further advancement of the secondary clocks when they reach a certain chronological position, and means including means controlled by said electro-magnet upon operation by the next successive additional uni-directional impulse 35 to render said restraining means ineffective, thereby permitting further advancement of said secondary clocks.

JAMES W. BRYCE.
